United States Patent Office

Des. 180,981
Patented Sept. 10, 1957

180,981

TOOTHPICK DISPENSER

Roland Williams, San Francisco, Calif.

Application June 29, 1956, Serial No. 42,085

Term of patent 14 years

(Cl. D44—24)

FIG.2

FIG.1

Figure 1 is a perspective view of a toothpick dispenser, showing my new design;

Figure 2 is an elevational view of the toothpick dispenser; and

Figure 3 is a top plan view.

I claim:

The ornamental design for a toothpick dispenser, as shown.
